CLAIM

The ornamental design for a dog pooper scooper rod, as shown and described.

DESCRIPTION

FIG. 1 is a front, disassembled view of a dog pooper scooper rod in accordance with the present design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof;

FIG. 7 is an assembled, perspective view of the dog pooper scooper rod;

FIG. 8 is a front view thereof;

FIG. 9 is a rear view thereof;

FIG. 10 is a left side view thereof;

FIG. 11 is a right side view thereof;

FIG. 12 is a top plan view thereof; and,

FIG. 13 is bottom plan view thereof.

The broken lines depict environmental features for illustrative purposes only and form no part of the claimed design.
